UNITED STATES PATENT OFFICE

PERCY E. HUNTER, OF PITTSBURGH, PENNSYLVANIA

HIGHWAY GUARD

Application filed February 10, 1932. Serial No. 592,016.

My invention relates to fences or guard railings and the like and is especially suitable for use along highways, bridges, etc.

One object of my invention is to provide a fence or railing structure that is particularly adapted to withstand the impacts of vehicle wheels, bumper bars, etc.

Another object of my invention is to provide a structure of relatively inexpensive construction which possesses great strength compared to the weight of material employed.

Still another object of my invention is to provide an improved manner of fastening rails to supporting posts.

A further object of my invention is to provide a structure of generally improved form which is also of pleasing appearance.

Some of the forms which my invention may take are shown in the accompanying drawings wherein Figure 1 is a front elevational view of a portion of a fence; Fig. 2 is a vertical sectional view of the structure of Fig. 1; Fig. 3 is a view taken on the line III—III of Fig. 2, on an enlarged scale; Fig. 4 is a view taken on the line IV—IV of Fig. 2, on an enlarged scale; Fig. 5 is a view similar to Fig. 2, but showing a modification; Fig. 6 shows a modification of the structure of Fig. 1; Fig. 7 is a vertical sectional view of the structure of Fig. 6; Fig. 8 is an enlarged view, taken on the line VIII—VIII of Fig. 7; Fig. 9 is an enlarged view taken on the line IX—IX of Fig. 7, and Fig. 10 is a vertical sectional view showing still another modification of the structure.

Referring first to Figs. 1 to 4, I show a railing structure which includes a main post 11, which is of I-beam form, the lower end of which is imbedded in concrete or the like and has anchor rods 12 connected thereto, which are also imbedded in the concrete. It will be understood, of course, that when employed on bridges, the posts may be bolted or otherwise secured to the structural members of the bridge.

Bottom rails 13, here shown as angle bars, are connected to the posts by means of tie bars or splice plates 14 which extend through perforations in the webs of the posts 11 and are connected at their ends to the horizontal

flanges of the rails 13, by means of bolts 15. Each tie bar 14 is offset or bent at its mid portion, and after the tie bar is slid into position in the post, a key 16 is also inserted into the slot to hold or to wedge the bent or recessed portion of the tie bar in snug engagement with the adjacent surface of the post, the offset portion of the tie bar thereby being caused to serve as stops for preventing longitudinal shifting of the rails 13 and the tie bar relative to the post. The key 16 is retained in position by one of the bolts 15, as shown more clearly in Fig. 1.

Intermediate rails 17 may suitably be of sheet metal stamped or rolled to generally channel form, but having their upper flanges 18 of considerably greater width than their lower flanges 19. The intermediate or buffer rails 17 are located at such distance above the road surface that they will receive the impact of vehicle wheels, bumpers, etc.

These rails are positioned with their webs against the outer faces of the posts 11 and their flanges 18 overlying the upper ends of said posts. The lower flanges 19 of the rails are cut away somewhat adjacent to the edges of the posts to permit the webs of the rails to lie against the faces of the posts.

The rails 17 are connected to the posts by means of tie plates or splice bars 21 whose intermediate portions are bent or offset at 22. The web of each post 11 is provided with a vertical slot at its upper end into which the offset 22 of the tie bar may be inserted. The tie bar is secured to the rails 17 by means of bolts 23 and 24, the bolts 24 extending also through the flanges of the post 11.

An upper or hand rail 26 of sheet metal or other suitable material is supported by post members 27 which are shown as of channel form. The post members 27 are secured to the rear flanges of the posts 11 by bolts or rivets 28.

The top rail 26 is provided with a depending flange 29. The flanges 29 of the top rail sections 26 are connected together by tie bars 30 which are offset at 31, the offset portion of the tie being dropped into vertical slots in the upper ends of the posts 27. The ends of each tie bar 30 are secured to the rail sec-

tions 26 by means of bolts 32, and bolts 33 serve to connect the rail sections, the tie bars and the posts directly together.

The upper flange 18 of the intermediate rail 17 is bent vertically at its rear edge, for attachment to the flanges of the upper post members 27 by rivets or bolts 35. Pickets 36 are secured to the flanges of the rails 26 and the flanges of the rails 17. Similarly, 10 pickets 37 are secured at their ends to the lower flanges 19 of the intermediate rails 17 and to the vertical flanges of the lower rails 13.

The tie bars 21 serve not only to support 15 the intermediate rail sections in proper position with respect to the posts 11, but also function as tension members to transmit tensile stresses from one rail section to another. Thus, if a vehicle runs against a mid portion 20 of one of the rail sections 17, the tie bars will function as tension members for transmitting stresses to adjacent rail sections; and the series of intermediate rail sections, 25 together with the tie bars, will function as a cable to resist impacts and to prevent permanent deformation of the rail section that receives the impact of a vehicle, particularly if the rail sections are of sheet metal and have some flexibility.

The intermediate rail 17 is particularly suited to serve as a buffer for receiving the impact of vehicle wheels, etc., even though of comparatively light material, because of 30 its flanges 18 and 19, which resist bending stresses, and particularly because of the flange 18 which is of great width compared to the flanges of ordinary channel rails. Furthermore, the widened flange 18 permits of placing the post section 27, the top rail 26 and the pickets 36 far enough rearwardly 35 of the impact-receiving surface of the rail 17 that they will not ordinarily be engaged by any portion of a vehicle which may collide with the intermediate rail.

The flange 18 of the intermediate rail not only gives added strength by reason of its width, but increases the architectural beauty of the structure, and serves to shed water and snow.

Referring now to Fig. 5, I show a structure that is similar to that of Figs. 1 to 4, but wherein the top rail 26a has a horizontally-extending flange 29a, and the intermediate rail 17a has flange portions extending horizontally at 18a and 19a, so that pickets 36a and 37a may be pressed into perforations contained in said flanges instead of making it necessary to rivet or bolt the pickets in place as in Fig. 1. In this structure, the bottom rail 13a has its upper flange turned horizontally for the reception of the lower ends of the pickets 37a. The upper flange of the rail 13a is connected to the posts in the same manner as is the bottom rail 13.

In Figs. 6 to 9, I show a structure wherein

main posts 40 are employed, in the form of hollow castings. These posts are suitably imbedded in the roadway or secured thereto in any other suitable manner. At their lower ends, the posts have their sides perforated 70 for the reception of the ends of bottom rail sections 41 and tie bars 42. The tie bars are offset at their mid portions and are first inserted through the perforations in the posts. The ends of rail sections 41 are then inserted and are secured to the tie bars 42 by bolts 43. The rails and the tie bars snugly fit the perforations so that the offset shoulder portions of the tie bar serve as stops to prevent longitudinal shifting of the rail sections 41 with respect to the posts.

Intermediate rail sections 44 which may be formed similarly to the rail sections 18 have their ends in abutting engagement with the sides of the posts 40. Each post 40 is perforated for the reception of a tie bar 45 that is offset at its mid portion and which has its offset shoulders held in snug engagement with the sides of the posts by key bars or wedges 46, the members 44, 45 and 46 being connected together by means of bolts 47.

By this arrangement, it is not necessary that bolt holes or specially-formed lugs, flanges, clips, or fin plates be provided in the post 40 for the connection of tie bars and rails thereto, since the arrangement of the tie bar and key bars securely hold the rails in position on the post. The tie bars 44 in this structure function also as tension members as described in connection with the tie bars of Figs. 1 to 4, to transmit longitudinal stresses. A cap or top plate 48 is provided for each post.

The upper flanges 50 of the intermediate rail sections 44 are connected to each other by a tie bar 51 (Fig. 8) whose ends are fastened to the flanges 50 and which are connected to the posts by bolts 52. The mid portion of each tie bar 51 is offset and lies in perforations formed in the flanges of an upper post member 53, the bolts 52 extending also through the web of the post section 53, and through a key plate 54 that holds the offset portion of the tie bar 51 in close-fitting engagement with the post 53. The post section 53 is further connected to the post 40 by bolts 55.

Upper rail sections 56 are secured to the post members 53 in a manner similar to that in which the rail sections 26 are mounted and pickets 57 and 58 are mounted in place similar to the manner in which the pickets 36 and 37 are positioned.

In Fig. 10, I show a railing structure 125 wherein main posts 80 of concrete are provided on bridge structures, and may be provided along a highway, if desired, to support upper and lower rails 81 and 82, respectively, and intermediate rails 83, pickets 130 84 and 85 being mounted in place similar

- to the manner in which the pickets 36 and 37 of Fig. 1 are positioned. The intermediate rails 83 are formed similarly to the rail sections 18, so that the upper rails 81 and 5 pickets 84 will be positioned rearwardly of the impact-receiving surface of the rail 83. Tie bars or splice plates 86 and 87 are imbedded in the posts 80 adjacent to their upper and lower ends, respectively, and extend 10 outwardly from the sides of the posts, for connection with the ends of the upper and lower rail sections 81 and 82, respectively. The intermediate rails 83 are connected to the posts 80 by means of tie plates 88, the 15 ends of the rails being bolted or otherwise secured to the ends of the tie plates. The transmission of tensile stresses from one rail section to another is afforded by the tie bars, in the same manner as heretofore described.
- 20 I claim as my invention:—
1. Fence structure comprising posts, a buffer rail secured to said posts, adjacent to the upper ends thereof, and upper guard railing structure secured to the rear side of the posts.
  - 25 2. Fence structure comprising posts, a buffer rail secured to the front sides of said posts, and upper guard railing structure mounted in a vertical plane adjacent to the rear sides of said rail and posts.
  - 30 3. Fence structure comprising a buffer rail of channel form, with its web portion disposed in a vertical plane, and having one flange of greater width than the other flange, and pickets secured to said flanges.
  - 35 4. Fence structure comprising a buffer rail of channel form, with its web portion disposed in a vertical plane, and having its upper flange extending upwardly and rearwardly from the said web.
  - 40 5. Fence structure comprising a buffer rail of sheet metal, in the form of a channel having its web portion disposed in a vertical plane, and having a rearwardly-extending flange whose width is not less than the width 45 of said web.
  6. Fence structure comprising a top rail, an intermediate rail of channel form, a bottom rail, pickets connected to the top rail and one flange of the intermediate rail, and 50 pickets connected to the bottom rail and the other flange of the intermediate rail, the first-named pickets being located rearwardly farther than the second-named pickets.
  - 55 7. Fence structure comprising main posts, a buffer rail of channel form secured to the front sides of and overlying the upper ends of said posts, and a guard railing structure extending upwardly from the rear edge of said rail.
  - 60 8. Fence structure comprising a buffer rail, a lower panel disposed in a plane rearwardly of the vertical face of the buffer rail, and an upper panel disposed in a plane rearwardly 65 of said buffer rail and rearwardly of the vertical plane of the first-named panel.
  9. Fence structure comprising main posts, upper post sections mounted at the rear sides of the main posts, a buffer rail secured to the main posts adjacent to the front sides thereof, and panel members secured to the upper post 70 sections.
  10. Fence structure comprising a buffer rail of channel form and having an upwardly and rearwardly-extending flange portion, and means for supporting pickets adjacent to the rear edge of said flange portion. 75
  11. Fence structure comprising a buffer rail, a lower panel disposed beneath the said rail, and an upper panel disposed above the rail in a plane rearwardly of the vertical face 80 of said rail and rearwardly of the lower panel.
  12. Fence structure comprising a buffer rail having an approximately vertically-disposed face, and having a flange portion extending upwardly and rearwardly from the said face. 85
  13. Fence structure comprising a buffer rail having an approximately vertically-disposed face, a flange portion extending upwardly and rearwardly from the said face, and means affording vertical support to the said flange at points rearwardly of said face. 90
- In testimony whereof I, the said PERCY E. HUNTER have hereunto set my hand. 95
